RELAY

Carl H. Larson, Elkhart, Ind., assignor to The
Adlake Company, a corporation of Illinois

Application May 22, 1938, Serial No. 275,008

2 Claims. (Cl. 200—97)

This invention relates to mercury switch relays and in order to understand the objects of the invention, it is necessary to define certain terms that will be used:

5 *Normal operate time* is the time required to produce a change in the electrical circuit through the switch when the relay winding is suddenly closed while all parts of the switch are lying in stable equilibrium.

10 *Normal release time* is the time required to produce a change in the electrical circuit through the switch when the relay winding is suddenly opened while all parts of the switch are lying in stable equilibrium.

15 *Normal operate recycling time* is the minimum period during which the relay winding must be permitted to remain open in order that the normal operate time is obtainable when the relay winding is suddenly closed. Usually, though not always, the normal operate recycling time is the same as the time required for the switch elements to reach stable equilibrium after the relay winding has been opened.

20 *Normal release recycling time* is the minimum period during which the relay winding must be permitted to remain closed in order that the normal release time is obtainable when the relay winding is suddenly opened. Usually, though not always, the normal release recycling time is the same as the time required for the switch elements to reach stable equilibrium after the relay winding has been closed.

25 *Quick operate reset* refers to the ability of a switch to give normal operate time without requiring a particular time interval to precede the closing of the relay winding.

30 *Quick release reset* refers to the ability of a switch to give normal release time without requiring a particular time interval to precede the opening of the relay winding.

35 Obviously in writing commercial specifications for relays of this kind, minimum and maximum values are often given for operate and release time, these values representing time intervals which must be met regardless of the relative positioning of the switch parts (i. e. in stable equilibrium or not) at the instant that the condition of the electrical circuit through the relay winding is changed. The minimum values are usually specified to prevent an immediate change in circuit condition in the event of sub-normal recycling conditions, and the maximum values are usually given to hold the operation of the relay to reasonable cycles or to meet some other special operating condition.

With the above definitions in mind, it is broadly the object of this invention to provide a mercury switch relay that can fulfil certain relay specifications that have heretofore been impossible to meet, at least with relays of this type. 5 To accomplish this end, two time delay elements are used in such a way that their action is correlated, and the action of one modifies or affects in some way the action of the other.

More specifically, it is an object of this invention to provide relays which are characterized by being able to meet certain minimum operate and release time requirements, and also embody quick reset features either in connection with operate time or release time. 10

15 There are other objects and advantages inherent in the relays herein disclosed, as will be apparent from the description which follows, taken in conjunction with the accompanying drawings, in which—

20 Fig. 1 is a vertical, sectional view through a front contact mercury switch relay constructed in accordance with the teachings of this invention, the switch parts being shown in their normal position of equilibrium with the relay coil de-energized. 25

25 Fig. 2 is a view corresponding to Fig. 1, but showing the position which the switch parts assume immediately after the relay coil has been energized. 30

30 Fig. 3 illustrates the manner in which the relay insures that the prescribed minimum release time will elapse before the circuit through the switch is broken.

35 Fig. 4 is a view similar to Fig. 3, but showing an intermediate position of the switch parts during the time that the minimum release time is running.

40 Fig. 5 is a horizontal, sectional view taken on the line 5—5 of Fig. 1; 40

45 Fig. 6 is a diagrammatic illustration of a circuit which can advantageously use a relay of the type shown in Figs. 1-5 inclusive;

50 Fig. 7 is a vertical, sectional view through a back contact relay embodying the principles of this invention, the switch parts being shown in their normal position of equilibrium with the coil de-energized;

55 Fig. 8 is a view showing the manner in which the back contact form of the relay insures minimum operate time; and

60 Figs. 9 and 10 are diagrammatic illustrations of circuits which will be used in explaining the functioning of the back contact switch shown in Figs. 7 and 8. 65

Certain preferred forms of the invention have been illustrated in the drawings and will be hereinafter described in compliance with Section 4888 of the Revised Statutes, but the invention is not limited to the specific disclosure contained herein, and the appended claims should be construed as broadly as the prior art will permit.

Front contact relay (Figs. 1-5)

- 10 Before describing in detail the front contact relay shown in Figs. 1-5 inclusive, it will be helpful to explain briefly an electrical circuit that requires the use of a relay of the type in question. The electrical circuit, of course, is merely illustrative of many such circuits that require relays of unusual operating characteristics of the kind which the present relay possesses.
- 15 Referring, then, to Fig. 6, a load is shown at 20 which is controlled by the combined action of 20 a relay 21 having certain time delay characteristics and a relay 22 of the fast acting type. The relay 21 is a front contact relay having its coil connected across lead wires 23 and 24, but in series with the contacts generally designated 25, 25 of the relay 22. The contacts, generally designated 26, of the relay 21 are connected across the leads 23 and 24, but in series with the operating coil of the relay 22, and the load 20 is connected across this latter coil.
- 30 Upon energizing the leads 23 and 24, the relay 21 closes the contacts 26 after a predetermined time interval (normal operate time) which in turn energizes the relay 22 and operates the load 20. The relay 22, however, is a quick make, 35 quick break, relay which immediately upon energization, opens the contacts 25. This results in de-energization of the operating coil for the relay 21. Hence the contacts 26 are again opened, but this reopening of the contacts 26 must not take place until a certain minimum 40 time has elapsed to energize the load 20. This minimum time determines the specified minimum release time for the relay 21.
- 45 Stated in other words, any energization of the leads 23 and 24, if sustained a sufficient length of time causes the load 20 to be operated for a given interval of time (minimum release time for the relay 21), but only after a given time interval has elapsed subsequent to the energization of the leads 23 and 24 (normal operate time for the relay 21). Hence the relay 21 in so far as its function has thus far been described, must have a predetermined normal operate time and a predetermined minimum release time. In addition to these characteristics, the relay must also have quick operate reset characteristics so that if the leads 23 and 24 are first energized and then de-energized before the contacts 26 have had an opportunity to close, the prescribed normal operate time will elapse between the second energization of the leads 23 and 24 and the closing of the contacts 26. Summarized, the relay 21 must have the following operating characteristics: It must be a front contact relay with predetermined normal operate time, predetermined minimum release time, and have quick operate reset, so that normal operate time will be obtained even under subnormal operate recycling conditions.
- 70 The relay shown in Figs. 1-5 inclusive has these characteristics.
- 75 It comprises a coil 27 provided with poles 28 and 29 within which the relay switch generally designated 30 is suitably mounted.
- 75 The switch 30 comprises a switch envelope 31

of low expansion, boro-silicate glass through the base of which lead-ins 32 and 33, preferably of molybdenum or tungsten, are pinch-sealed. The lead-ins project upwardly into the switch envelope and are covered for portions of their lengths by insulating sleeves 34 and 35, respectively, leaving exposed electrodes 36 and 37 which are adapted to be bridged and unbridged by appropriate manipulation of the mercury fill 38 within the envelope.

A glass thimble, generally designated 39, is telescoped over the electrode 37 and is fused to the sleeves 34 and 35, as indicated at 40. The thimble is provided with a relatively large opening 41 at one side to permit mercury to pass 15 freely to and from the thimble except only as the movement of the mercury is retarded by the action of a time delay element 42 which consists of a gas pervious plug of ceramic material, preferably Alundum, Grade RA 98 (manufactured by the Norton Company of Worcester, Massachusetts), bonded by fusion, or other suitable means, into an opening provided in the upper end of the thimble. The plug offers a predetermined impedance to the flow of gas to and from the thimble whenever the mercury in the envelope complete covers the opening 41 and the plug is, of course, impervious to mercury.

The electrode 37 extends above the insulating sleeve 35 and is surrounded by a ceramic cup 43 which is bonded to the upper end of the insulating sleeve 35 and forms a reservoir for a small pool of mercury 44 which is always in contact with the electrode 37 and permits the bridging of the electrodes 36 and 37 to be accomplished by a mercury to mercury contact.

The mercury fill 38 within the displacer is manipulated by a magnetically controlled plunger or displacer, generally designated 45, which comprises an inner glass thimble 46 closed at its upper end by a porous wall 47 which constitutes a second time delay element within the switch. The thimble 46 has an iron sleeve 48 telescoped over it, and constituting the armature of the relay. The armature is split on one side as indicated at 49, so that the relay may be used efficiently with alternating current, and the armature is held in place upon the thimble 46 by upper and lower cushioning springs 50 and 51, respectively, which clamp guide washers 52 and 53 in place against the ends of the iron sleeve. The springs 50 and 51 frictionally engage the projecting ends of the thimble 46 and effectively hold the component parts of the displacer in assembled relation. The guide washers 52 and 53 have prongs 54 which guide the displacer in its movement within the envelope, and the peripheral cuts 55 between the prongs permit mercury to pass freely by the washers between the displacer and the switch envelope.

The switch envelope before being sealed off at 56, is filled with a suitable inert gas, such as helium, hydrogen, or the like, or a mixture of such gases.

The operation of the switch is illustrated in Figs. 1-4 inclusive, and particular attention should be paid to the function which the side opening 57 in the thimble 46 has in giving the relay its desired operating characteristics.

Assuming that the switch parts are in stable equilibrium with the coil de-energized (as shown in Fig. 1) the first thing that happens upon energization of the coil is the lowering of the displacer to the position in which it is shown in Fig. 2. Since the opening 57 in the displacer 7

thimble 46 is submerged in the mercury fill during the downward movement of the displacer, gas is trapped within the upper portion of the displacer, and the result is that the mercury level within the displacer is forced down to a position indicated at 58, and the outside mercury level rises to the position indicated at 59. Assuming now that the coil 27 remains energized, the mercury within the displacer thimble tends to rise due to the equalization of the gas pressures within and outside of the displacer thimble, and the time that is required for the inside mercury level to reach the top margin 60 of the opening 41 is determined solely by the impedance which the time delay element 47 in the displacer thimble 46 offers to the passage of gas escaping from the thimble. Thereafter, the movement of mercury upwardly within the fixed thimble 39 to close the contacts through the switch, is determined by the joint action of the time delay element 47 in the displacer thimble 46 and the time delay element 42 in the fixed thimble 39. These two time delay elements are chosen with porosities effecting a total elapse of time, such that the time required for the mercury to rise from the level indicated at 58 up to and into contact with the mercury pool 44 is equal to the specified normal operate time of the relay. If the relay coil continues to be energized, stable equilibrium is finally reached when the mercury level throughout the switch is equalized at the level indicated by the line 61.

However, when the relay is recycled through its own contacts, as in Fig. 6, the mercury level within the thimble 39 rises only to a height sufficient to close the contacts, at which instant the relay coil is de-energized through contacts 25 of the relay 22. The first thing that happens under these circumstances is that the displacer 45 rises because of its buoyancy to the position shown in Fig. 3, where it is momentarily retarded in its upward movement by reason of the fact that the total effective weight of the displacer includes the mercury column that is carried up within the displacer during its upward movement. It should be noted that this position of the displacer is lower than the normal de-energized position of the displacer and also that the outside mercury level indicated at 62 is above the opening 57 in the displacer thimble 46. As gas slowly enters the displacer through the porous wall 47, the mercury within the thimble 46 gradually recedes, lessening the effective weight of the displacer and causing it to slowly rise until the opening 57 reaches the outside mercury level 62, as indicated in Fig. 4. During this time, the circuit between the electrodes 36 and 37 remains closed. At the instant that the switch parts reach the position shown in Fig. 4, gas is permitted to enter the interior of the displacer through the side opening 57 which in effect bypasses the time delay element 47 and immediately causes the mercury within the displacer to fall to the level in which it is shown in Fig. 1 and simultaneously therewith, the displacer rises to its full height, as shown in Fig. 1.

The time required for the displacer to move to the position shown in Fig. 3 and then with retarded motion reach the position shown in Fig. 4 and finally move swiftly to the position shown in Fig. 1, determines the minimum time that the circuit through the electrodes 36 and 37 when once closed is permitted to remain closed, or in other words, this function of the relay determines the minimum release time of the

relay. For the circuit shown in Fig. 6, the minimum release time is only .6 of a second, which for all practical purposes, is substantially no time delay at all.

In my prior Patent 1,967,947, a displacer is shown which has somewhat the same characteristic action as the one disclosed in the present application, but the relay there shown does not have the peculiar operating characteristics that are obtained by the use of two time delay elements working together. For example, it is impossible with the relay shown in Patent No. 1,967,947 to have a minimum operate or release time because subnormal recycling conditions can under certain circumstances bring about a substantially instantaneous closing of the circuit upon a change in the condition of the relay coil. As proof of this fact, suppose that the time delay element associated with the displacer in Larson No. 1,967,947 is designed to give a sixty second time delay between the closing of the relay coil and the making of the circuit through the electrodes, and that the relay specifications call for a minimum time delay of sixty seconds when making the circuit, if after thirty seconds of that time has elapsed, the relay coil is de-energized, the plunger will immediately rise and carry with it a column of mercury that will at once bridge the contacts. The relay of my prior patent, therefore, is incapable of insuring that the contacts will not close before the elapse of a specified minimum operate or release time. By way of contrast, if the mercury level in the present invention has almost reached the mercury pool 44 associated with the electrode 37 at the instant that the coil 27 becomes de-energized, the substantially instantaneous rise of the displacer 45 and concurrent falling away of the mercury level to the position in which it is shown in Fig. 1 insures that the relay will not make a false contact.

There is a possibility that when the specified minimum release time is relatively high, a particular positioning of the switch parts at the instant that the relay is de-energized, would result in a false making of the circuit through the switch. To that extent, the particular relay disclosed has a limitation, but if on the other hand, the operating characteristics do not require a minimum release time, as is many times the case, the opening 57 may be placed at a sufficiently high level, so that whenever the coil is de-energized, it at once rises above the outside mercury level and undermines the column of mercury within the displacer. In this way, there is no possibility for the contacts to be bridged by mercury without the elapse of the minimum operate time following the energization of the coil.

It is obvious that when the hole 57 is placed sufficiently high in the displacer thimble 46 so that there is an instantaneous, or at least substantially instantaneous drop away of mercury from the contacts upon de-energization of the coil 27, the switch has what is termed quick operate reset inasmuch as every energization of the coil will always produce the required normal operate time irrespective of the time during which the coil was previously de-energized.

By way of specific example, if the relay 21 of Fig. 6 requires a normally open contact with a normal operate time of 3.5 seconds, and a minimum release time of .6 second with a quick operate reset feature, the time delay element 47 in the plunger may have a .4 second time delay 75

(time required to produce stable equilibrium in the switch after the coil has been energized, assuming that the fixed thimble 39 were omitted) and the time delay in the fixed thimble 39 may have a time delay of 3.1 seconds.

If a longer minimum release time were required, the opening 57 might be provided with a ceramic plug similar to the plug 47, or if a shorter minimum release time were required, the hole 57 could be raised proportionately to within this result. Obviously, these values are necessarily determined empirically in actual practice.

Back contact relay

15 In Figs. 9 and 10, diagrammatic illustrative circuits are shown requiring back contact relays having somewhat unusual operating characteristics.

20 In Fig. 9, by way of example, the relay 70 may, because of the apparatus which it controls, be required to have its contacts 71 close with a normal release time of 3.5 seconds and open with a normal operate time of .6 second, regardless of the operating characteristics of the control contact 72. Or the relay 70 may be used 25 in a self re-cycling circuit such as shown in Fig. 10, in which case the relay must have a quick release reset. The relay shown in Figs. 7 and 8 is satisfactory for use with either of these circuits assuming that the time delay elements are 30 properly chosen for values and the side opening in the displacer is suitably positioned.

35 The construction of the relay is identical with the relay shown in Figs. 1-4 inclusive with the exception that the parts are differently proportioned, and the displacer relief vent 57 is located in a bulge 73 provided in the lower portion of the displacer thimble. Inasmuch as the parts of this relay are functionally the same as those 40 in the relay shown in Figs. 1-4 inclusive, like reference characters will be used, and further description of the structure is unnecessary.

45 It is obvious that when the relay coil is energized, the displacer in moving to the position shown in Fig. 8 carries with it momentarily a column of mercury, but almost instantaneously, the side vent 57 admits gas to the interior of the displacer, thereby undermining the mercury column in the displacer. The release of mercury 50 from the displacer 45 allows the displacer to rise further thereby lowering the level of the mercury fill to a point below the mercury opening in the thimble. The mercury column within the thimble is thus undermined and falls immediately, 55 breaking the circuit through the electrodes. The short interval required for the mercury column to be undermined by the gas entering the displacer through the vent 57 enables the minimum operate time of .6 second to be met.

60 If a longer minimum operate time is required, the vent 57 may be equipped with a porous plug to delay the admittance of gas to the interior of the displacer. If a shorter minimum time delay is desired, the vent 57 may be located at a 65 higher level.

65 Again, the situation exists that if the relay has a substantial minimum operate time requirement, the ability of the switch to have a quick release reset is limited. On the other hand, when 70 the minimum operate time is relatively small, the

quick release reset is capable of being achieved.

The combination of a time delay in a plunger with a time delay fixed to the electrode, makes it possible to obtain time delays on both the opening and closing of the contact, which otherwise would be impossible to produce. It is, of course, possible to produce a delay on both opening and closing of a contact with a time delay on either the electrode or the plunger alone, but not with quick reset features. An additional 10 advantage is that when the time delays on both make and break have to be held to very close limits, the time delays may be individually adjusted without one time delay adjustment interfering with the other.

15

In both front and back contact forms of the invention, the limitation in the quick reset characteristics of the switches may be avoided and are avoided by using circuits in which the recycling of the relay is controlled by the switch 20 contacts. For example, by using the circuit shown in Fig. 6 for the front contact switch of Figs. 1-5 inclusive, the switch functions with quick operate reset, and when the circuit shown in Fig. 10 is used for the back contact switch 25 of Figs. 7 and 8, the switch functions with quick release reset.

25

I claim:

1. In a mercury switch relay having prescribed operating characteristics, the combination of a 30 relay coil, a switch associated with the coil, said switch comprising a switch envelope, spaced electrodes in the envelope, a mercury fill, a hollow displacer responsive to the coil for shifting the mercury level, and cooperating time delay elements associated with one of said electrodes to delay the movement of mercury with relation to said electrode upon a change in the condition of the electrical circuit through the coil, one of said time delay elements comprising a gas leakage device associated with the displacer, and the other comprising a relatively fixed gas leakage device associated with said one electrode, and means including at least one of said time delay 35 elements for maintaining the column of mercury above said one electrode for a predetermined time to insure that, once the electrodes have been bridged with mercury, they will remain bridged for at least a brief period of time.

40

2. In a mercury switch relay having prescribed operating characteristics, the combination of a relay coil, a switch associated with the coil, said switch comprising a switch envelope, spaced electrodes in the envelope, a mercury fill, a hollow displacer responsive to the coil for shifting the mercury level, and cooperating time delay elements associated with one of said electrodes to delay the movement of mercury with relation to said electrode upon a change in the condition of the electrical circuit through the coil, one of said time delay elements comprising a gas leakage device associated with the displacer and the other comprising a relatively fixed gas leakage device associated with said one electrode, and means including at least one of said time delay 50 elements for insuring that the switch shall possess minimum operate time characteristics.

55

3. In a mercury switch relay having prescribed operating characteristics, the combination of a relay coil, a switch associated with the coil, said switch comprising a switch envelope, spaced electrodes in the envelope, a mercury fill, a hollow displacer responsive to the coil for shifting the mercury level, and cooperating time delay elements associated with one of said electrodes to delay the movement of mercury with relation to said electrode upon a change in the condition of the electrical circuit through the coil, one of said time delay elements comprising a gas leakage device associated with the displacer and the other comprising a relatively fixed gas leakage device associated with said one electrode, and means including at least one of said time delay 60 elements for insuring that the switch shall possess minimum operate time characteristics.

65

CARL H. LARSON. 70
